UNITED STATES PATENT OFFICE.

JOHN C. NEIKIRK, OF LOMBARD, ILLINOIS, ASSIGNOR TO RODGER BALLAST CAR COMPANY, OF CHICAGO, ILLINOIS, A CORPORATION OF MAINE.

SELECTIVE DUMP CAR.

Application filed July 14, 1924. Serial No. 725,962.

The present invention relates to selective dump cars.

This type of car permits the selective dumping of lading between the tracks upon which the car is mounted or outside of said tracks. Such cars commonly include rotatable shafts extending in planes at right angles to one another for operating the various dump doors. More particularly the present invention relates to mounting means for said operating shafts.

An object of the present invention is to provide mounting means for shafts whose axes occupy planes at right angles to one another.

A further object is to provide a railway car construction in which two shafts whose axes occupy planes at right angles to one another may be sturdily mounted in a unitary structure.

A further object is to provide a railway dump car having center sills in which said center sills may be used to good advantage in rotatably supporting a pair of shafts whose axes lie in planes at right angles to one another.

A further object is to provide shaft mounting means for the dumping mechanism of a railway dump car, which shaft mounting means will be cheap to manufacture and install and which will be sturdy and well adapted to withstand the shocks encountered in service.

Further objects will appear as the description proceeds.

Referring to the drawings—

Figure 1 is a transverse sectional view of part of a railway dump car;

Figure 2 is a view of a detailed construction of the mechanism shown in Figure 1;

Figure 3 is a transverse sectional view taken along a different plane than that shown in Figure 1 and illustrating the two shafts whose mounting means constitutes the subject matter of the present invention;

Figure 4 is a sectional view taken along the plane indicated by the line 4—4 of Figure 3; and

Figure 5 is a sectional view taken along the plane indicated by the line 5—5 of Figure 3.

The numerals 7—7 indicate the center sills of a railway dump car. Said sills 7—7 have mounted adjacent thereto the downwardly and outwardly sloping floors 9—9 consti-

tuting parts of two hopper bottoms disposed laterally of the sills 7—7.

The numerals 11—11 indicate portions of the dump doors which may be opened for dumping between the tracks upon which the car is mounted. The mechanism for dumping laterally of the tracks upon which the car is mounted is not shown in the present drawing, inasmuch as the details of this construction form no part of the present invention.

Disposed longitudinally of the car below the center sills is the shaft 16, which for convenience of construction may be square in cross section. Mounted upon the square shaft 16 is the crank member 23, illustrated detached in Figure 2. Said crank member 23 is provided with the cylindrical portion 25, which is carried by the depending loop member 26, which loop member 26 may be suitably supported from the lower inner flanges of the center sills 7—7. Said crank member 23 is provided, at the extremities of the cylindrical portion 25, with the crank arms 27 and 28. As will be noted from an inspection of Figure 1, the crank arm 27 is connected through a series of links with one of the dump doors 11 and the crank arm 28 is connected through a different series of links with the other dump door 11. The details of construction of the crank member 23 and the links through which said crank members are connected to the dump doors 11—11 need not be described herein, inasmuch as they do not form any part of the present invention.

Mounted in a plane extending transversely of the car is the shaft 31, which is illustrated as being round in cross section but which may be of any desired cross section. The construction will be described, however, in connection with the round shaft 31. Said shaft 31 extends through the webs of the center sills 7—7 and is provided intermediate of its webs with the worm 35 non-rotatably fixed to said shaft 31. Any preferred means for non-rotatably connecting the worm 35 to the shaft 31 may be employed, bolts for that purpose being illustrated in Figure 3.

To provide a bearing for the shaft 16 and for the shaft 31 and to form a support for the mechanism associated therewith, a supporting member 36 is provided, which supporting member 36 includes a strap secured

to the inner sides of the center sills 7—7, the lower inner flanges of the sills 7—7 being cut away to receive said supporting member 36. Said supporting member 36 is formed by first longitudinally slotting a metal plate intermediate of the ends thereof and then bending said plate intermediate of its ends into the general form of a V, so that the solid ends 37—37 of the V form means for attaching said supporting member 36 to the inner sides of the center sills 7—7, while the intermediate portions comprise legs 38—38 of V-shaped conformation having rounded apexes. Mounted within the legs 38—38 of the supporting member 36 are the bushings 39—39, which may be provided with annular collars 40—40 to limit movement of said bushings 39—39 longitudinally of the shaft 16. Said bushings 39—39 may have cylindrical peripheries for rotation in the legs 38—38 and may have rectangular apertures extending therethrough for fitting upon the square shaft 16. Mounted above the bushings 39—39 and between the two sides of the supporting member 36 are the hold down bearing members 41—41, each of which has a general V shape having its apex reversely disposed, as indicated by the numeral 42, to conform to the corresponding bushing 39. The legs of the V-shaped bearing members 41—41 are riveted to the legs of the supporting member 36 and are also riveted through the end portions 37—37 of the supporting member 36 to the center sills 7—7, thus forming strong bracing members, as well as suitable upper bearings for the bushings 39—39. In the event that a round shaft 31 is used, such shaft may be journaled for rotation in suitable holes in the ends 37—37 of the supporting member 36. Said ends 37—37 also serve to limit endwise movement of the worm 35 and shaft 31.

Mounted upon the shaft 16 between the bushings 39—39 is the worm wheel 45, which has meshing engagement with the worm 35, the hub of which worm wheel 45 bears against the collars 40—40 of the bushings 39. Cotter pins 46—46 are provided for limiting movement of the bushings 39—39 and the worm wheel 45 longitudinally of the shaft 16.

In installations as formerly provided involving a shaft for operating link mechanism for opening and closing dump doors such as the dump doors 11—11, trouble has been experienced due to the fact that workmen will sometimes attempt to rotate the shaft in the wrong direction. Workmen will often apply considerable force, exerted through a large leverage, to turn the shaft in the wrong direction, which action often has destructive results on the mechanism of the car. The present invention contemplates means whereby such destructive results are rendered impossible. The worm

wheel 45 is provided with a pair of abutments 46—46 mounted on the side faces thereof offset from the axis of said worm wheel, which abutments may be conveniently provided by a pin inserted through the worm wheel 45 and extending laterally from the two side faces thereof. Located in cooperative relationship with the abutments 46—46 of the worm wheel 45 are the shoulders 47—47, which extend inwardly from the two legs 38—38 of the shaft support 36. The shaft 16 in common constructions will require something less than a complete revolution in turning from full closed to full open position, or from full open to closed position. For this reason the abutments 46—46 and shoulders 47—47 may be so designed as to limit the extent of rotation of the worm wheel 45 to the amount required for the opening and closing movements of the dump doors. If a workman should attempt to turn the operating shaft 31 in the wrong direction either for opening or closing movement, such movement would be prevented by reason of the engagement between abutments 46—46 and shoulders 47—47, so that destructive forces cannot be applied in any such manner to the link mechanism for operating the doors 11—11.

It will be noted that a construction is provided which is sturdy and which is cheap to manufacture. Through a preferred embodiment of the present invention has been described in detail, many modifications will occur to those skilled in the art. It is intended to cover all such modifications that fall within the scope of the appended claims.

What is claimed is:

1. A railway dump car, comprising a pair of center sills, a shaft extending through said sills transversely thereof, a worm carried by said shaft, a supporting member comprising a strap slotted to provide a pair of depending legs and a worm wheel mounted between said legs and meshing with said worm.

2. A railway dump car, comprising a pair of center sills, a shaft extending through said sills transversely thereof, a worm carried by said shaft, a supporting member comprising a strap slotted to provide a pair of depending legs and a worm wheel mounted between said legs and meshing with said worm, said strap being provided with a holding member conforming thereto for providing hold down means for said worm wheel.

3. A railway dump car, comprising center sills, a pair of shafts extending in planes substantially at right angles to one another, a supporting member carried by said sills, said supporting member comprising a bifurcated member of V-shaped conformation providing a pair of depending legs, a worm on one of said shafts and a worm wheel on

the other of said shafts, said worm wheel being mounted between said depending legs, said supporting member being provided with a hold down member conforming in shape 5 to said holding member for providing an upper bearing to prevent upward movement of said other shaft.

4. A railway dump car, comprising spaced center sills, a shaft holding member having 10 a V-shaped conformation and having a portion disposed between and secured to the inner sides of said center sills, said V-shaped member having its apex formed to provide a rounded bearing portion, said V-shaped 15 member being bifurcated at its apex to provide spaced legs to permit mounting therebetween of a power transmitting member.

5. A railway dump car, comprising spaced center sills, a shaft holding member having 20 a V-shaped conformation and having a portion disposed between and secured to the inner sides of said center sills, said V-shaped member having its apex formed to provide a rounded bearing portion, said V-

shaped member being bifurcated at its apex 25 to provide spaced legs to permit mounting therebetween of a power transmitting member, and a hold down member riveted to each of said legs for providing an upper bearing member.

6. A shaft support for railway door operating mechanism, comprising a substantially V-shaped member having a lower shaft bearing at its apex and an upper hold-down bearing member mounted within the 35 V-shaped member and secured thereto, said apex being slotted to provide a pair of spaced legs providing between them a gear receiving space.

7. A shaft support for railway dump car 40 door mechanism, comprising a slotted plate bent to substantial V-shape to form shaft bearings at its apices, and a gear receiving space between the apices.

Signed at Chicago, Illinois, this 10th day 45 of July, 1924.

JOHN O. NEIKIRK.
